UNITED STATES PATENT OFFICE.

JOHN JAMES WARREN, OF BROWNVILLE, NEW YORK.

METHOD OF AND APPARATUS FOR CONTROLLING THE PULP IN THE PIT OF A WOOD-PULP GRINDER.

Application filed March 4, 1924. Serial No. 696,782.

To all whom it may concern:

Be it known that I, JOHN J. WARREN, a citizen of the United States, residing at Brownville, in the county of Jefferson, State of New York, have invented certain new and useful Improvements in Methods of and Apparatus for Controlling the Pulp in the Pit of a Wood-Pulp Grinder; and I do hereby declare the following to be a full, clear, and exact description of the invention, such as will enable others skilled in the art to which it appertains to make and use the same.

This invention relates to the grinding of wood into the so-called "mechanical" pulp used in the manufacture of newsprint and other cheap papers, and in particular it relates to the control of the pulp in the pit below the grindstone. The present application is a continuation in part of my copending application, Serial No. 594,501, filed October 14, 1922.

Immediately below the grindstone, a wood-pulp grinder is usually provided with a pit which first receives the ground pulp, and in which the lower face of the grindstone is submerged. When the pulp is thin it flows readily from the pit and keeps itself of substantially uniform consistency. When, however, less grinding water is used and the pulp becomes too thick to flow easily it often forms in heavy masses, causing the water to run away in channels, thus permitting the grindstone to become overheated, with the possibility of fracturing. Also, small pieces of wood, commonly known as slivers, are sometimes carried between the bottom of the wood cutting compartment and the grindstone, and into the pit, where they collect, rubbing against the surface of the stone and burning it, thus destroying its cutting surface. Furthermore, when this condition of the pulp prevails the dry portion of the stone gets filled with dry wood pulp, or what is known as wood flour and cannot clear itself, and be kept in the proper cutting condition.

It is, however, advantageous to work with a thick pulp. A thick pulp is more efficient than a thin pulp in cleaning the face of

the stone and keeping it in cutting condition; moreover, I have discovered that when the pulp is thick, longer and stronger fibers are formed, probably due in part to the fact that the grinding is performed at a higher temperature which steams and softens the logs.

It is, therefore, the object of this invention to do away so far as possible with the objectionable features commonly attendant upon the use of thick pulp. I do this by placing an agitator in the pit under the grindstone so as to keep as nearly as practicable to a very uniform consistency of pulp, and to aid in carrying the mass of thick pulp under the stone forward so that a uniform consistency will be presented to the grindstone preventing slivers or thick pulp from diverting the shower water and causing it to travel in streaks or around the stone. To accomplish this purpose satisfactorily it is necessary to revolve the entire mass of stock under the stone to a considerable extent, thereby mixing in the water necessary for grinding purposes, and presenting as nearly as possible a uniform pulp to the grinding surface, and particularly to enable the operator to keep a thicker consistency in the pit than if operating without an agitator.

In order to control the consistency of the pulp in the pit, it is customary to add water. It is a further object of this invention to provide improved means for doing this. The water, in accordance with the present invention is sprayed against a deflecting plate or flash-board depending from the grindstone housing. This plate not only spreads the water but prevents this water, which is quite cold compared to the grindstone, from striking the stone and thus possibly fracturing it.

A preferred embodiment of the invention is illustrated in the accompanying drawings in which Fig. 1 is a transverse vertical section through the lower end of a magazine grinder constructed in accordance with the grinder of my application; and Fig. 2 is a vertical section taken at 90° from the plane of the section of Fig. 1.

The grinder shown in these figures comprises the ordinary cylindrical grindstone 21 enclosed within a housing 24, mounted on a shaft 22, and journaled in water cooled bearings 23. The stone is securely fixed upon the shaft by means of bushings 25 and concave steel flanges 26. Adjustably mounted on the housing 24 and located centrally over the grindstone is a vertical magazine 29 into the upper end of which is placed the wood to be ground. This wood is positively and continuously forced against the grindstone by means of a series of endless chains 30, two located on each of the two opposite sides of the magazine parallel with the shaft 22. The operation of these chains has been described in detail in my application and will not be repeated here as it forms no part of the present invention.

20 Situated immediately below the grindstone is a pit 27 into which the ground pulp from the stone first passes, and into which the lower face of the stone is partly submerged as shown. To control the depth of the pulp in the pit, I have provided at the discharge side thereof, a swinging dam 28, which may be raised or lowered by any suitable means, thus regulating the position of the overflow.

25 30 Situated immediately below the grindstone and within the pulp in the pit, I have provided in accordance with this invention, an agitator 91. This agitator comprises an endless belt or band of substantially the same width as the pit made up of a series of straps 103, to which are secured a series of transverse bars or cleats 104, the whole passing about two series of rollers 105. A shaft 106 upon which one of the series of 35 rollers is mounted, extends through a side wall of the pit as shown in Fig. 2, and is rotated from the shaft 22 by means of a gear reducer 107. This belt moves the mass of pulp toward the point of discharge and 40 keeps it of uniform consistency even when the pulp is too thick to flow readily itself.

45 Within the housing and located in front of the grindstone is a spray pipe 82, through 50 which water is added to the pulp in the pit to control its consistency. Depending from the top of the housing and located between the pipe 82 and the grindstone is a swinging flash-board or deflecting plate 81, the lower edge of which is serrated or toothed. The 55 water sprayed from the pipe 82 strikes this flash-board and, spreading out, is distributed across the width of the pit. At the same time, this spray is prevented from coming into direct contact with the hot stone and possibly checking or fracturing it. By 60 making the lower edge of the flash-board serrated or toothed, a better distribution of the added water across the width of the pit is effected.

By the means described above, I am enabled to obtain a more complete and satisfactory control of the pulp within the pit than has heretofore been possible.

I claim:

1. In a wood-pulp grinder, the combination of a grindstone, a pit beneath the grindstone for receiving the ground pulp, and means in the pit for agitating the pulp and keeping it of substantially uniform consistency. 75

2. In a wood-pulp grinder, the combination of a grindstone, a pit beneath the grindstone for receiving the ground pulp, and an endless belt in the pit for agitating the pulp and preventing the accumulation of slivers or heavy stock, and the formation of channels. 80

3. In a wood-pulp grinder, the combination of a grindstone, a rotary shaft supporting said grindstone, a pit beneath the grindstone for receiving the ground pulp, an endless belt in the pit for agitating the pulp and preventing the accumulation of slivers or heavy stock and the formation of channels, and means for operating the agitator from the grindstone shaft. 85

4. In a wood-pulp grinder, the combination of a grindstone, a pit beneath the grindstone for receiving the ground pulp, and an endless belt in the pit of substantially the same width as the pit and extending across it in a substantially horizontal plane for agitating the pulp and preventing the accumulation of slivers or heavy stock, and the formation of channels. 100

5. In a wood-pulp grinder, the combination of a grindstone, a pit beneath the grindstone for receiving the ground pulp, and an endless belt in the pit for agitating the pulp and preventing the accumulation of slivers or heavy stock, and the formation of channels, transverse bars or cleats on the belt, and rollers about which the belt passes. 105

6. In a wood-pulp grinder, the combination of a grindstone, a pit beneath the grindstone for receiving the ground pulp, a spray pipe for introducing additional water to the pulp in the pit, and a flash-board between the grindstone and the spray pipe for shielding the stone and distributing the water. 110

7. In a wood-pulp grinder, the combination of a grindstone, a pit beneath the grindstone for receiving the ground pulp, a spray pipe for introducing additional water to the pulp in the pit, and a flash-board between the grindstone and the spray pipe for shielding the stone and distributing the water, the lower end of the flash-board being serrated or toothed. 115

8. In a wood-pulp grinder, the combination of a grindstone, a pit beneath the grindstone for receiving the ground pulp, a point of discharge in the pit for the pulp, and 120

125

means within the pit for moving the pulp toward the discharge and keeping it of substantially uniform consistency.

9. An improvement in the method of 5 grinding wood pulp by forcing the wood against a rotating grindstone in the presence of water, and passing the pulp through a pit in which the grindstone runs partly

submerged, which comprises reducing the grinding water to a point where the pulp is too thick to flow readily while positively moving the thick pulp to the discharge point of the pit and agitating it to keep it of uniform consistency. 10

In testimony whereof I affix my signature.
JOHN JAMES WARREN.
